AMUSEMENT APPARATUS

Louis Hendrich, Valparaiso, Ind.

Application March 7, 1940, Serial No. 322,649

5 Claims. (Cl. 273—101)

My invention relates to improvements in standard. In ordinary practice this may be five or six feet high, more or less. At the upper end of the standard 1 where the shaft 4 projects consists of the features pointed out in the annexed claims.

The purpose of my invention is to provide an amusement device that comprises a standard of suitable height through which a motor driven shaft extends throughout its length and at the top of the standard radial arms of different lengths are attached to the shaft. Miniature airplanes are suspended in a detachable and attachable manner below the ends of the arms. At a distance from the standard or tower, one or more shooting stands may be placed. Each stand has an aiming post and controls for sprung pressed projectiles which are released by the player to bring down the airplanes as they are rapidly rotated by the motor attached to the shaft at the lower end of the standard. The airplanes are divided into separate groups, one group revolving at a given diameter, the next group at a little larger diameter, and each successive group being on a similar increased diameter of rotation. With these and other ends in view I illustrate in the accompanying drawing such instances of adaptation as will disclose the broad idea of the invention without limiting myself to the specific details shown thereon and described herein.

Fig. 1 is a side elevation of an assembled device.

Fig. 2 is a plan view of Fig. 1.

Fig. 3 is a detached detail of Fig. 1.

Fig. 4 is a view similar to Fig. 3 showing position changes.

Fig. 5 is a detached semi-perspective of a guiding plate.

Fig. 6 is an elevation partly in section of a "gun."

Fig. 7 is a modification of Fig. 6.

Fig. 8 is a diagrammatic view of a pair of guns for one ship.

Fig. 9 is a view similar to Fig. 8 showing a change of hook.

Fig. 10 is a diagrammatic view of a self-catching arrangement.

Fig. 11 is an enlarged detail of Fig. 10.

In marketing my amusement device I may utilize whatever equivalents or alternatives of construction or adaptation that the exigencies of varying conditions may demand without departing from the broad spirit of the invention.

The standard or tower 1 may be of any construction. It is secured to a suitable base 2 upon which a small motor 3 is fastened. This motor drives a shaft 4 that extends upward through the

standard. In ordinary practice this may be five or six feet high, more or less. At the upper end of the standard 1 where the shaft 4 projects radial arms 6 are secured to the shaft so as to rotate with it. As exemplified in the drawing, there are four different lengths of arms 6 so that the outer ends of each of the arms will move in its own selected zone. At the outer end of each arm a sheave 7 is secured on which the cord 8 rides. This supports the miniature airplanes by means of specially formed hooks 9 that project above the fuselages 10. There is also a sheave 11 on each arm 6, near the standard.

A supporting cord 8 of any desired material, is secured to the airplanes 13. It passes over the pulley sheaves 7 and 11 and drops down alongside the standard 1 on depending supports 14 which are secured to the radial arms 6. These supports

rotate with the arms 6. Suitable guides 15 are provided for the cords 8. Below the standard 1 are guides at a selected distance away, counterweights 16 are fastened to the cords. Below the counter-

weights 16 any form of ring may be fastened to serve as a handhold through which the cords are

operated to raise "shot-down" airplanes and bring them to their raised position. The safety cords 12 prevent a dislodged airplane from crashing to the ground when it is dislodged from its support.

The counterweights move upward at the same time the plane moves downward. The extent of the drop of a plane is limited by a counterweight 16 engaging the guide 15 which serves as a stop

(Figs. 1, 3 and 4).

In a large scale device operated in amusement parks, there will be an attendant to receive the cash, who will issue tickets including a certain number of shots; an attendant to raise the

dropped airplanes to their position on the hooks which depend beneath the outer ends of the radial arm; and another attendant to pick up the projectiles and return them to the shooting stands.

In order to prevent the bullets from injuring a ceiling should the device be operated in an enclosed space, a conical canopy 17 may be secured at the upper end of the driving shaft 4 of such a

diameter as to include the longest radial arms

6 (Fig. 1).

Any kind of an automatic restoring means 42 may be provided to guide the specially formed

hooks 9 attached to the top of a fuselage 19 onto the supporting means at the outer ends of the

radial arms 6. The attaching hooks 9 are specially shaped so that if a coordinate wing 19 of an airplane is hit by a bullet 20 the airplane will

be dislodged and free to drop (Figs. 10 and 11).

55

The shooting stands 21 may be connected by wires 31 or otherwise to a group of projectile holders 22 corresponding in number to the different radii of the moving airplanes. At each shooting stand there is a sighting pole 23 with a movable arm 24 that the player can direct to any one of the different zones. After having selected the desired zone, he releases a "charged" bullet 20 which is located directly beneath the zone in which he is operating. The skill of the player is manifested in his ability to time the release of the projectile in relation to the rapidly moving airplane in the fighting zone which he has selected (Figs. 1 and 2).

15 The projectiles or bullets 20 are of any desired material, rubber or otherwise, and they may be provided with a lengthwise hole 25. This hole permits assembling the bullets on a vertical rod 26 which is aligned directly beneath the airplane wing so as to lead the bullet against it and dislodge the airplane. The bullets may be inside of a tube 27 and the force for expelling them resides in a coil spring 28, in tube 27, below the bullet. Any desired means such as a long tube 29 to prevent stopping may be used for pressing the bullets against the spring so as to push it past a catch 30 that may be released through a cord or wire 31 by hand from the shooting stand or by means of an adapted foot treadle, 18 (Figs. 30 6 and 7).

In its simplest form there will be one bullet rod 26 for each zone of airplane movement. If more variety is desired two such rods may be provided for each zone. In this event the hooks of the airplane will be reversed so that a plane suspended below one end of a radial arm will become dislodged when a left wing is hit by a bullet but the duplicate plane at the other end of the arm will be dislodged by the bullet coming from the 40 second rod 26 hitting the right wing. This brings in an element of uncertainty so that the player will not know which wing he is going to hit. In other words duplicating the projectile rods in each zone produces an uncertainty which adds to the sport (Figs. 8 and 9).

If instead of using an automatic arrangement for attaching an airplane to the end of a radial arm 6, I may make the cord 8 with the counter-weight 16 to itself terminate beyond the sheave 7 in a guiding plate 32 having an opening 41 therethrough into which the hook 9 of the airplane will be inserted by an attendant as the cord is pulled down by hand. In this event the safety cord 12 would reach from the attaching end of the cord 8 to the airplane with sufficient slack to prevent the airplane crashing to the ground after being released (Figs. 3 and 4).

The standard 1 through which the driving shaft passes may simply be a tube of sufficient strength to sustain the weight of the radial arms and airplanes without being swayed out of its vertical position.

As an alternative the bullets 33 may be solid and instead of the guiding rod 26 referred to they may be inside of a tube 27. At any event, the spring 28 which furnishes the ejecting force must be compressed to the desired amount. When this point is reached a catch 30 comes into play to hold the spring in its compressed position until the player releases it. There are as many releasing means at the shooting stand as there are bullet holders associated with it. In the simplest case, one for each zone through which the airplanes fly and when greater variety is desired there may be two projectile holders 26 for each

zone, which, should there be eight radial arms, each one with two variable plane hooks there would be a total of sixteen releases (Fig. 7).

Only one shooting station is shown on the drawing but this is illustrative and it is obvious that more than one station may be used so that several players may enjoy the game at the same time (Fig. 2).

The speed of revolution of the suspended airplanes may be varied by any conventional means associated with the driving motor. It is probable that under certain formal regulations for tournaments, etc., that the speed of rotation will be definitely indicated on the entrance cards. Several teams may contest at a certain speed of rotation and the same teams or others may engage in a separate contest at another agreed-upon rotative speed.

Above the spring 28 a washer 34 is placed. This may be larger in diameter than the spring 20 so as to project outside of it. It passes below the catch 30 when the bullet is pressed against the spring. The catch 30 is part of a pivoted arm 35. It has a spring 36 adapted to hold the catch 30 in place. The position of the catch 30 in relation to its movement toward the washer 34 can be adjusted as needed by a limit screw 37. Whenever a guide tube 27 is used instead of a guide rod 26 a washer 38 is placed above the spring inside of the tube. A pin 39 projects from the washer. It moves in a long slot 40 and it projects out of the slot so as to be engaged by the catch 30 to hold the spring in its compressed position (Fig. 7).

What I claim is:

1. In an amusement apparatus, a supporting standard, a base therefor, a rotatable shaft extending throughout the length of the standard and projecting thereabove, a motor at the bottom end of the shaft to drive it, a plurality of radial arms of different lengths supported at the upper end of the shaft, a plurality of detachable and attachable miniature airplanes supported beneath the outer ends of the arms, a plurality of projectile holders spaced apart at distances corresponding to the difference in radial length of the arms, means for forcibly ejecting the projectiles from the holders as and when desired, a shooting station, a sighting post associated with the station and separate releasing means at the station for the several projectile holders.

2. In an amusement apparatus, a suitable standard, means for rotatably supporting the plurality of radial arms at the upper end of the standard, means for attachably and detachably securing miniature airplanes beneath the outer ends of the arms, means for counterweighting the airplanes independently of each other such means comprising a suitable cord or flexible cable, means for selectively dislodging airplanes from their support, and means for supporting the airplanes after dislodgement to prevent their becoming damaged through crashing on the ground.

3. An amusement device which comprises a raised standard, a plurality of different length radial arms pivoted above the standard for horizontal rotation, means associated with the standard for imparting motion to the arms, means for detachably and attachably positioning a miniature airplane beneath the outer end of each arm, a plurality of projectile holders positioned in spaced apart relation beneath the suspended planes and in approximate alignment with the ends of the radial arms.

4. An airplane amusement device comprising a

- suitable elevated standard, a shaft within the standard, means for rotating the shaft selectively, a plurality of different length radial arms attached to the upper end of the shaft, a pair of spaced apart sheaves on each arm, a cord traversable on the sheaves, a detachable and attachable airplane at the outer end of the cord, and a counterweight at the inner end of the cord.
5. A model airplane comprising an open sided hook secured to the top surface of an airplane fuselage, means for supporting the plane on said

hook in a detachable and attachable manner, a plurality of radial arms each arm having an airplane beneath its outer end, and means for rotating the arms and attached airplanes on a horizontal plane whereby each moving plane becomes a target for the impact of a "bullett" aimed to hit the wing on the open side of the hook to dislodge the plane and then score a point for each plane dislodged.
